United States Patent Office.

DAVID M. SMYTH, OF ORANGE, NEW JERSEY, ASSIGNOR TO O. P. DORMAN,
OF NEW YORK, N. Y.

Letters Patent No. 71,074, dated November 19, 1867.

IMPROVED MACHINE FOR CUTTING PAPER COLLARS.

The Schedule referred to in these Letters Patent and making part of the same.

TO ALL WHOM IT MAY CONCERN:

Be it known that I, DAVID M. SMYTH, of Orange, in the county of Essex, and State of New Jersey, have invented certain new and useful Improvements in Machinery for Cutting Paper Collars; and I do hereby declare that the following is a full, clear, and exact description thereof, reference being had to the accompanying drawings, making part of this specification, in which—

Figure 1 is a top view or plan.

Figure 2, an end elevation.

Figure 3, a side elevation; and

Figure 4, a longitudinal vertical section.

The same letters indicate like parts in all the figures.

My said invention relates to machinery for cutting collars successively from a sheet of paper, of a width equal to the length of the intended collar, the sheet being advanced or fed forward, at each operation, a distance equal to the width of one collar, to three pairs of shears, two of which cut off the corners to give the required form to the ends of the collar, and the other severs the collar from the sheet.

In the accompanying drawings, *a* represents a suitable frame, on the table *b* of which the sheet of paper is placed, from which collars are to be cut. On this table is mounted a sliding frame, consisting of two parallel bars *c c*, connected by cross-bars *d d'*. This frame slides between ways *e e*, and receives a longitudinal reciprocating motion in one direction by tappets projecting from the faces of two wheels *f f* on a shaft, *g*, one being on each side of the frame, and these tappets actuate two levers that bear against the projecting ends of the bar *d*, and so soon as the tappets have passed, the frame is moved back by the tension of a spring, *h*. To the middle of the bar *d'* is attached a spring-arm, *i*, in the back end of which is mounted a wheel, *j*, whose periphery is toothed, and which by the spring-arm *i* is borne on to the surface of the paper, so that when the frame is moved forward the teeth of the wheel *j* shall draw or push forward the sheet of paper the required distance, the wheel being prevented from turning by a spring-pawl, *k*, when the carriage moves in that direction, but which will permit it to turn freely and roll over the paper during the back motion. So soon as the sheet of paper is advanced or fed forward, as above stated, it is clamped and held to the surface of the table during the back motion of the feeding mechanism and during the shearing operation, and then liberated by a clamping-plate, *l*, secured to the forward end of two levers *m m*, one on each side of the table, and moving on fulcrum-pins projecting from the sides of the frame. The said levers are operated to depress the clamping-plate by means of tappet-wheels *n n*, on the shaft *g*, and in the opposite direction to lift the clamping-plate by means of springs that act on the shears to be presently described. Forward of the clamping-plate there are three pairs of shears *o o', p p',* and *q q'*. The two pairs, *o o'* and *p p'*, consist, each pair, of one stationary blade *o p*, and of one movable blade *o' p'*, the two blades being connected by a fulcrum-pin in the usual manner of connecting the two blades of a pair of shears. These two pairs of shears are curved in opposite directions, or otherwise shaped to suit the form required to be given to the ends of a collar. The movable blades *o' p'* have each an arm extending beyond the fulcrum-pin, and the one, *o'*, extends over the other as represented at *r*, so that any movement imparted to the one, *p'*, will be communicated to the other; and the outer shearing end of the blade *p'* is extended under one of the levers *m* of the clamping-plate, so that the shearing motion of the movable blades of these shears is derived from the levers of the clamping-plate, a spring, *s*, being connected with the extended arms of the blades to open them. The third pair of shears, *q q'*, are for shearing off the collars the required width, and they also consist of a stationary blade, *q*, and a movable blade, *q'*, connected by a fulcrum-pin like the other shears, and the movable blade extends beyond the fulcrum-pin, and is connected with one of the levers of the clamping-plate, to receive its shearing motion therefrom, as represented at *t*, a spring, *u*, being applied to open the shears, and which aids in lifting the clamping-plate. This pair of shears is represented as being straight, as paper collars are usually cut straight along the length, but if it should be desired to make collars curved, then the shears should be made of a corresponding curve.

By means of the combinations above described, paper collars can be cut of the form required, with clean, smooth edges, and with great rapidity, from a sheet of paper of any desired length.

What I claim as my invention, and desire to secure by Letters Patent, is—

The combination of the two pairs of hinged shears for shaping the ends of paper collars, with the pair of shears for cutting off the collars from a strip or sheet of paper, and the feeding mechanism, or the equivalent thereof, substantially as described.

And I also claim the toothed wheel with its holding-pawl, and connected with the sliding reciprocating frame by a spring-arm, or equivalent, in combination with the holding-clamp, substantially as and for the purpose described.

D. M. SMYTH.
